United States Patent Office

Des. 183,808
Patented Oct. 28, 1958

183,808

TOASTER OR SIMILAR ARTICLE

Paul O. Rawson, Jr., Trumbull, and Theodore G. Daher,
Stratford, Conn., assignors to General Electric Com-
pany, a corporation of New York

Application April 30, 1958, Serial No. 50,686

Term of patent 14 years

(Cl. D81—10)

Fig. 1.

Fig. 2.

Fig. 1 is a perspective view of a toaster embodying our new design showing the top, one side and one end thereof;

Fig. 2 is a perspective view of the Fig. 1 toaster showing the top, other side and other end thereof.

The dominant features of the design reside in the portions shown in full lines.

We claim:

The ornamental design for a toaster or similar article, substantially as shown and described.
